CLAIM

The ornamental design for a tarpaulin tie, as shown and described.

DESCRIPTION

FIG. 1 is a left side view of the tarpaulin tie;
FIG. 2 is a bottom plan view of the tarpaulin tie;
FIG. 3 is a top plan view of the tarpaulin tie;
FIG. 4 is a right side view of the tarpaulin tie;
FIG. 5 is an end view taken from the top of FIG. 3;
FIG. 6 is an end view taken from the bottom of FIG. 3;
FIG. 7 is a perspective view of the tarpaulin tie; and,
FIG. 8 is a top plan view of a second embodiment of the
design of FIG. 1, the only difference being the inclusion
of an additional circular element on the longer strap.
